CLAIM

The ornamental design for a charging device for medicament infusion pump device as shown and described.

DESCRIPTION

This application is related to U.S. application Ser. No. 29/776,662, filed Mar. 31, 2021, titled Charging Device For Medicament Infusion Pump Device, which is incorporated by reference and made a part of this specification.

FIG. 1 is a front, first side, and top isometric view of an embodiment of a charging device for medicament infusion pump device embodying the new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

Broken lines are used to illustrate features and/or environmental structures and form no part of the claimed design. Broken dot-dash lines are used to indicate a border of the claimed design and form no part of the claimed design. The broken lines immediately adjacent the claimed surfaces represent boundaries of the claim, which extends to the boundaries, but does not include the boundaries; all other broken lines depict portions of the charging device for medicament infusion pump device that form no part of the claim.

1 Claim, 5 Drawing Sheets
